William Taylor Jones, Scranton, Pa., assignor to Consolidated Molded Products Corporation, Scranton, Pa., a corporation of Delaware

Application August 16, 1956, Serial No. 42,627

Term of patent 7 years

(Cl. D29—19)

FIG. 1.

FIG. 2.

FIG. 3.

Fig. 1 is an elevational view of the obverse side of a medallion showing my new design;

Fig. 2 is an elevational view of the reverse side of the medallion; and

Fig. 3 is a cross-sectional view of the medallion taken along the lines 3—3 in Fig. 1, and looking in the direction of the arrows.

The dominant features of the design reside in the portion shown in full lines in the drawing.

I claim:

The ornamental design for a medallion, as shown and described.
